Elmer Stetler,

UNITED STATES PATENT OFFICE.

THOMAS HUNT, OF WILKES-BARRE, AND ELMER STETLER, OF PARSONS, PENNSYLVANIA.

SILK-DOUBLING MACHINE.

1,414,131.

Specification of Letters Patent. Patented Apr. 25, 1922.

Application filed September 25, 1920. Serial No. 412,628.

To all whom it may concern:

Be it known that we, THOMAS HUNT and ELMER STETLER, citizens of the United States, residing, respectively, in Wilkes-Barre and Parsons, in the county of Luzerne and State of Pennsylvania, have invented certain new and useful Improvements in Silk-Doubling Machines, of which the following is a specification.

10 This invention relates to machines in which silk is doubled by being wound on single spools, bobbins, or other receivers from a plurality of spools or other carriers of the material.

15 In some machines for that purpose, a plurality of spools or other carriers of the material forming the supply to the spools, bobbins, or other receivers on which the material is wound are supported on frames or the like arranged in substantially parallel relation to one another and at an inclination to the perpendicular.

20 When material from a spool or other carrier on a frame breaks, the loose end portion thereof is liable to, and frequently does, become involved with material passing from carriers on an adjacent frame, and the result is interference with the proper operation of the machine and faulty product wound on the receivers.

25 30 It is an object of the invention to avoid such occurrences by providing means to prevent broken or loose parts of the material from coming into such contact with properly moving material as will result in entanglement.

35 40 When read in connection with the description herein, the characteristics of the invention will be apparent from the accompanying drawing, forming part hereof, wherein an embodiment of the invention is disclosed, for purposes of illustration.

45 Like reference-characters refer to corresponding parts in the views of the drawing, of which—

50 55 Fig. 1 is a fragmentary front elevation of a machine having the invention associated therewith; Fig. 2 is a front elevation of a carrier-frame formed in accordance with the invention; and Fig. 3 is a side elevation thereof.

Having more particular reference to the drawing, A designates a silk-doubling machine of conventional form, having spindles B carrying spools, bobbins, or other re-

ceivers C on which is wound silk material passing through guides D from spools or other carriers E on pins F of frames G.

The frames G are positioned in substantially parallel relation to one another at an 60 inclination to the perpendicular, one above every guide D, and the material passing from the carriers converges as it moves to the guides. One reason for disposing the frames at an inclination is to avoid contact 65 of the strands of material passing from the several carriers until it has reached or nearly reached the guides.

If a strand of material breaks between a carrier and a guide, the portion depending from the carrier is apt to swing toward the carriers on the next adjacent frame toward which its own frame is inclined. If breakage occurs near the bottom of a frame in material from an upper carrier, and thus 70 there is left a comparatively long depending free or loose portion, there is greater liability of entanglement with material of the next adjacent frame than when the depending portion is short, as, of course, the arc of 75 swing is greater.

With a view of preventing such entanglement, means are interposed by the invention between the frames. Each frame G has an arm 4 extending laterally therefrom toward 80 the next adjacent frame, the arm preferably being integral with its frame. A pin or spindle 5 extends from the free end portion of each arm, in substantially parallel relation to and of about the same length as the 85 carrier-spindles F. A roller 6 is carried by and is rotatable on each of the pins 5, and preferably it is of polished or smooth porcelain, as that material has been found capable 90 of contact with silk material without adherence thereto.

A roller so located operates to prevent the depending portion of broken or loose material from swinging over against material of an adjacent frame. For the reason hereinbefore explained, the rollers or guides are placed on lower portions of the frames as shown.

Having thus described our invention, what we claim as new, and desire to secure by 105 Letters Patent, is—

1. In a silk-doubling machine, the combination, with receivers on which material is wound, and frames disposed at an inclination holding carriers of the material being 110

supplied to said receivers, of rollers between said frames arranged to prevent loose portions of material on one frame from swinging into contact with material on an adjacent frame.

2. In a silk-doubling machine, the combination, with receivers on which material is wound, and frames disposed at an inclination holding carriers of the material being supplied to said receivers, of rollers between the lower portions of said frames arranged to prevent loose portions of material on one frame from swinging into contact with material on an adjacent frame.

3. In a silk-doubling machine, the combination, with receivers on which material is wound, and frames disposed at an inclination holding carriers of the material being supplied to said receivers, of an arm extending from each frame toward an adjacent frame, a pin on said arm, and a roller journaled on said pin arranged to prevent loose portions of material on one frame from swinging into contact with material on an adjacent frame.

In witness whereof we affix our signatures.

THOMAS HUNT.
ELMER STETTLER.
